INFLATABLE TEST PLUG

Elmer F. Schuldt, Chicago, Ill.

Original application April 2, 1937, Serial No. 134,563, now Patent No. 2,192,155, dated February 27, 1940. Divided and this application December 20, 1937, Serial No. 180,698

3 Claims. (Cl. 138—93)

This application is a division of my copending application, Serial No. 134,563, filed April 2, 1937, now Patent No. 2,192,155 of February 27, 1940, for Method of and means for locating leaks in a gas main or the like.

This invention relates to a method and means for locating leaks in gas mains, underground fluid transmission conduits and the like, and more particularly is concerned with the location of fluid leaks in low pressure distribution mains. In the parent application, identified above, the means and apparatus disclosed and claimed make possible a material reduction of time and labor necessary for locating and repairing leaks in low pressure gas mains and the like, and the principal object of the present invention is the provision of a new and improved form of stopper or test plug which, while especially useful in connection with the above mentioned method and apparatus, is capable of other uses in connection with the stoppage of fluid flow through a conduit.

More specifically, it is an object of this invention to provide an inflatable test plug of simple and sturdy construction and which can be readily inserted through a relatively small opening in the main to be tested or plugged, and it is a further object of the present invention to provide a construction of this character which can be inserted through relatively long distances in the pipe.

Particularly, it is an object of this invention to provide an inflatable test plug which includes an interior spring member connecting the ends of the inflatable bag so as to facilitate the projection of the bag to the point desired. Another object of the present invention in this connection is the provision of pipe engaging means for the bag. An inflatable test bag of this construction is especially useful where it is the first of a series of bags connected together. It is also an object of the present invention to provide such an inflatable test bag with new and improved means for transmitting fluid under pressure through the bag but entirely out of communication with the interior of the bag. A bag of this character is especially adapted for use with other bags where it may be desired to determine the pressure conditions between two or more of such bags, as in the use of my method of locating leaks disclosed in the above identified parent application. A bag of this character, however, is not necessarily limited to such use.

The above and other advantages of this invention will be apparent to those skilled in the art

after a consideration of the following detailed description of the preferred means in which the principles of my invention have been embodied.

In the accompanying drawings:

Figure 1 is a longitudinal sectional view of one form of inflatable bag, which can be used for the rear bag in the apparatus disclosed in my parent application;

Figures 2 and 3 are enlarged sections taken along the lines 2—2 and 3—3, respectively, of Figure 1;

Figure 4 is a longitudinal sectional view of another form of bag, which can be used for the leading bag in the apparatus of my parent application;

Figure 5 and 6 are enlarged sections taken along the lines 5—5 and 6—6 of Figure 4.

Referring now more particularly to Figure 1, in testing pipes, such as gas mains and the like, for leakage it is usually desirable to stop off the pipe or main at one or more points in order to perform the desired tests, and in the accompanying drawings the reference numeral 30 indicates, by way of illustration, a gas main in which a test opening is made, as at 32, through which an inflatable test unit may be inserted, consisting either of a single bag in case the main 30 is merely to be plugged or consisting of two or more bags in case certain tests are to be made on sections of the main 30. Preferably, the main 30 is closed by any sealing compound 33, such as soap or the like.

One type of inflatable test plug incorporating the principles of the present invention is indicated in Figure 1 by the reference numeral 34. The test plug 34 includes an expandable bag or bulb 35 having nipple-like ends 36 and 37, the nipple end 37 enclosing a tubular metallic bushing or sleeve member 40 to the outer end of which a fitting 41 is secured, as by welding or the like. The fitting 41 is threaded and receives a coupling nut 42 to which is secured a coupling member 45 having two conduit sections 46 and 47 incorporated therein. Each of these conduit sections comprises a tube which extends into the fitting 41, the latter having two bores 48 and 49 to snugly receive the inner ends of the tubes 46 and 47, and the inner end of the coupling member 45 has a flange 51 which the outer end of the coupling member 42 engages. Preferably, a gasket 53 provides a leak-tight connection at this point.

The coupling member 45 forms one end of a dual-ported conduit, indicated in its entirety by the reference numeral 56. The conduit 56 is

provided with two generally parallel bores or tubes 57 and 58 which communicate, respectively, with the tube sections 46 and 47. Preferably the conduit member 56 is formed of molded rubber or the like and the tubes 57 and 58 are preferably in the form of copper or similar flexible tubes which are embedded in the rubber of the conduit member 56. In order to provide for propelling the inflatable test plug 34 for considerable distances within a main, the flexible conduit member is provided with a steel tape 60 extending along the member 56 and fastened by screws 61 or the like to the coupling member 45. The conduit member 56, either with or without the steel tape 60, is sufficiently flexible to permit inserting the unit 34 through the opening 32 in the main 30 and pushing it along on the inside, and if it is desired to know the distance that the unit 34 has been moved, the steel tape 60 may be provided with graduations 62.

A bushing or sleeve member 70 is disposed within the other nipple-like end 36 of the bag 35, and if desired suitable clamps 71 and 72 may be used for securing the bushings or sleeve members 40 and 70 to the bag 35. A spring member 73 is rigidly and permanently secured in any desired manner, as by welding or the like, to the bushings or sleeve members 40 and 70 and serves thereby to determine the actual length of the inflatable bulb or bag 35. Since one end of the spring member 73 is permanently and rigidly fastened to the sleeve 40, and since the latter is, in turn, rigidly fastened to the coupling member 45 to which the pushing tape 60 is connected, it will be seen that the members 60, 45, 40, 73 and 70 form one continuous spring member by which thrusts may be applied to shift the inflatable unit 34 from place to place within the main 30 and that the resiliency of the spring parts 60 and 73 permit the unit to accommodate bends, curves, elbows and the like in the main 30.

One of the conduit tubes, such as the tube 47, communicates through the sleeve or bushing member 40 with the interior of the inflatable bag 35, and the other tube 46 communicates with a tube 75 to which a flexible section 76, preferably formed of rubber or the like, is secured. The end of the section 76 opposite the tube 75 is connected to another tube 77 which leads into the sleeve member 70 and out of the latter at 78 so as to be in communication with the space in the gas main 30 beyond the unit 34.

In operation, the unit 34 as shown in Figure 1 may be inflated by compressed air or other source directed thereinto through the tubular sections 58 and 47, and if desired, access to the space in the gas main beyond the unit 34 may be had through the tubular sections 46 and 57, and the traversing tubes 75, 76 and 77. It will be noted that the latter extend from one end of the inflatable bag 35 to the other but are entirely out of communication with the interior thereof.

Where an inflatable test plug of this kind is to be used in association with another unit, as in the apparatus disclosed in my copending parent application, another conduit section, indicated in its entirety by the reference numeral 80 may be connected to the bushing or sleeve member 70. To this end, the conduit 80 may be cemented or otherwise secured or fastened to a coupling member 81 which is threaded, as at 82, to the outer end of the bushing 70. The coupling member 81 also receives one end of a resilient spring member 83 which extends along

the conduit 80 on the inside thereof and, in effect, forms a continuation of the resilient spring member 73 and the tape 60. Either or all of the spring members 60, 73, and 83 may be flat, or they may take the form of a helically coiled resilient member. In all cases, however, the spring members should be so formed as to be capable of transmitting thrusts and to permit pushing the unit 34, together with any other unit or units connected therewith, to be moved from place to place in the main 30 as desired.

The principles of the present invention can also be incorporated in the form of inflatable test plug shown in Figure 4, which is constructed so as to operate with the unit 34 described above. However, so far as the present invention is concerned, neither inflatable unit is limited in its application to an association with the other, inasmuch as either may be used separately if desired and as conditions warrant.

Referring now to Figure 4, for convenience of illustration I have shown my second form of inflatable test plug as attached to the conduit member 80 referred to above. The inflatable test plug of Figure 4 is indicated in its entirety by the reference numeral 100 and includes an expandible bag or bulb 101 having nipple-like ends 102 and 103. Within the end 102 is a bushing or sleeve member 105, the outer end of which is threaded, as at 106, and receives a coupling member 107 to which the ends of the conduit member 80 and the spring member 83 are attached. As will be clear from Figures 1 and 4, opposite ends of the member 80 are substantially identical in construction. The other end 103 of the expandible bulb 101 is provided with a bushing or sleeve member 110, and a flat spring member 111 is connected at opposite ends to the bushing or sleeve members 105 and 110 in any suitable manner, such as welding, brazing, or the like. Clamp members 113 and 114 may be provided for securing the nipple-like ends 102 and 103 to the associated bushings 105 and 110. As will be clear, the spring member 111 serves as an extension of the spring member 83, and likewise is not necessarily a flat member but may be a helically wound spring member if desired. Where the two inflatable test units 34 and 100 are used together, the inflating pressure for both of the bulbs 35 and 101 may be transmitted from the tube 58 to the first bulb 35 and from the latter through the conduit section 80 to the bulb 101. If used separately, the bulb 101 may be inflated in any suitable manner by fluid transmitted through the conduit section 80 from any convenient source, and if used with the unit 34, that source may be the same source from which the unit 34 is inflated, namely, the tube 58.

In order to facilitate the use of the unit 100 as a first of a series and to guide the same through bends, curves, elbows and the like in the main 30, the bushing or sleeve member 110 is provided with suitable pipe engaging guiding means. At its outer end, the member 110 is recessed, as indicated at 120, to receive the reduced end 121 of a guide supporting member 122. The member 122 has a groove 123 formed in its reduced end, and a transverse pin 125 is disposed in the outer end of the bushing 110 and is received in the groove 123 so as to hold the member 122 in position axially but to permit the same to rotate with respect to the member 110. Secured to the forward end of the member 122 is an elongated resilient arm member 128 which enters into a slotted

portion in the end of the member 122 and is secured therein by means of a pair of rivets 130. The outer or forward end of the elongated resilient arm member 128 is provided with a suitable pivot pin 132 upon which two oppositely disposed semi-spherical roller members 133 are mounted for free rotation.

By the provision of the guiding member 128, as a push is exerted upon the spring member 83 and transmitted to the spring member 111, rollers 133 will guide the unit 100 around bends or the like in the gas main 30. This construction is especially advantageous where offsets to clear a vault or underground manhole are encountered, in which case the unit or units must be guided through 45° and by the provision of the rollers 133, this can be accomplished without any substantial buckling or distortion of the parts.

The gas bags or bulbs 35 and 101 are preferably made of a material, such as rubber or the like, which may be treated to prove a wear-resisting surface, and all joints and connections may be cemented, if desired, in order to insure against loss of pressure.

While I have described above the preferred means in which the principles of the present invention have been embodied, it is to be understood that my invention is not to be limited to the particular details shown and described but that, in fact, widely different means may be employed in the practice of the broader aspects of my invention.

What I claim, therefore, and desire to secure by Letters Patent is:

1. A test plug for gas mains and the like comprising an inflatable bulb, a bushing secured with-

in each end of said bulb, a spring member extending from one end of the bulb to the other end and fastened to said bushings, means connected with one bushing and reacting through said spring member to propel the bulb along the 5 interior of a pipe, and pipe-engaging supporting means connected with the other bushing.

2. A test plug for gas mains and the like, comprising an inflatable body member having oppositely extending small diameter nipple portions 10 at opposite ends thereof, a small diameter bushing disposed within each of said nipple portions, cylindrical clamps of small diameter for securing said nipple portions to said bushings in leak-tight relation, and a flexible spring rod of fixed 15 length joining the bushings whereby said test plug may be inserted through an opening in said main of a diameter not substantially larger than the diameter of said cylindrical clamps by bending said spring rod.

3. A test plug for gas mains and the like, comprising an inflatable body member having oppositely extending small diameter nipple portions 20 at opposite ends thereof, a small diameter bushing disposed within each of said nipple portions, 25 a flat resilient longitudinally extending spring member disposed within said inflatable body portion and secured at its opposite ends within each of said bushings, and cylindrical clamps of small diameter for securing said nipple portions to said 30 bushings in leak-tight relation, whereby said test plug may be inserted through an opening in said main of a diameter not substantially larger than the diameter of said cylindrical clamps.
